UNITED STATES PATENT OFFICE.

CLOYDE A. MALLERNEE, OF DENNISON, OHIO.

FLOOR-TOOL.

1,278,702.

Specification of Letters Patent. Patented Sept. 10, 1918.

Application filed May 10, 1916. Serial No. 96,651.

To all whom it may concern:

Be it known that I, CLOYDE A. MALLERNEE, a citizen of the United States, residing at Dennison, in the county of Tuscarawas and 5 State of Ohio, have invented new and useful Improvements in Floor-Tools, of which the following is a specification.

This invention relates to tools of that type primarily adapted for removing floor boards 10 for installation of electric wires, gas pipes and other work requiring the displacement or removal of such boards.

The primary object of the invention is the provision of a floor tool which shall be simple in construction, durable in use, manufactured and sold at comparatively minimum cost, and so designed to permit of the removal of the floor boards without damaging or marring the same.

Another object of the invention is the provision of a device of the above stated character provided with a pair of spaced anchors, the spacing of the anchors forming the tool with a socket adapted to permit of a chisel 25 or other sharp edge tools being used in connection with my device.

With the above and other objects in view, the invention consists in the novel features, details of construction and combination of 30 parts which will hereinafter be more fully set forth, illustrated in the accompanying drawing and pointed out in the appended claims.

In the drawing:

Figure 1 is a fragmentary perspective view of a series of floor boards showing my improved floor tool inserted therebetween and in the act of removing certain of said boards;

Fig. 2 is a perspective view of the floor tool; and

Fig. 3 is a side elevation, clearly illustrating the anchors.

Referring more particularly to the accompanying drawing, in which like characters of reference refer to corresponding parts in the several views, 5 denotes my floor tool generally constructed from a single piece of tempered steel providing a flat rectangular base 6 bent angularly along one transverse edge thereof to provide a handle 7 stamped out at 8 forming an opening for the inser-

tion of the hand of the user to either convey the tool from place to place or permanently holding the same in supported position during the use of the tool. By providing the base portion 6 of flat formation, will greatly facilitate a firm contact of the underneath portion thereof upon the floor boardings when the tool is assembled for use, as 60 better shown in Fig. 1 of the drawing. It is my object to so construct or design the tool as to permit of the same being readily inserted between the seams of the boards to hold the same in position, and to this end, I 65 provide a pair of spaced longitudinally aligned anchors 9 and 10 respectively. These anchors are formed by bending one of the longitudinal edges of the base in a downward and angular position and the space 70 formed between the anchors is offset inwardly to form a U-shaped tool socket 11. The purpose of such socket is to enable the use of a sharp-edged cutting tool, preferably a chisel, designated by the character 12, 75 whereby after the anchors 9 and 10 are inserted between the seams of the boards and inserted therebetween a sufficient depth to anchor the tool, the chisel 12 is thence placed within the tool socket 11 and accomplishes 80 the displacement or removal of one of such boards, for installing electric wires, gas pipes and similar work. In briefly describing the operation of this invention, it is to be stated the board is first sawed from joist to joist, 85 and the tool is used as a guard against marring one board in removing the adjacent one from its original position. Without this guard, the imprint of the chisel is customarily embedded in the board on which the chisel rests, and the device is adapted to hold the cutting tool in place while prying the board loose.

From the foregoing description, taken in connection with the accompanying drawing, the advantages of construction and of the method of operation will be readily apparent to those skilled in the art to which the invention relates, and while I have described the principles of operation of the invention, together with the device which I now consider to be the best embodiment thereof, I desire to have it understood that the device shown is merely illustrative, and that such

changes may be made when desired as are within the scope of the claims appended thereto.

What is claimed, is:

- 5 1. A device of the class described comprising a flat plate having a pair of anchors on one edge, said anchors being spaced apart to permit the passage of a tool between them, and a handle on said plate.

2. A device of the class described comprising a flat plate having a pair of anchors projecting downwardly from one edge, said anchors being spaced apart and the edge between said anchors being curved downwardly to form a space to receive a tool, and a handle on said plate. 10 15

In testimony whereof I affix my signature.
CLOYDE A. MALLERNEE.
